UNITED STATES PATENT OFFICE.

JOHN H. YOUNG, OF RANDOLPH, NEW YORK, ASSIGNOR TO BORDEN'S CONDENSED MILK COMPANY, OF NEW YORK, N. Y., A CORPORATION OF NEW JERSEY.

SHEET-FEEDING MACHINE.

1,218,034.

Specification of Letters Patent. Patented Mar. 6, 1917.

Application filed December 10, 1913. Serial No. 805,712.

To all whom it may concern:

Be it known that I, JOHN H. YOUNG, a citizen of the United States, residing at Randolph, in the county of Cattaraugus and 5 State of New York, have invented a new and useful Sheet-Feeding Machine, of which the following is a specification.

My invention relates to improvements in sheet-feeding machines by aid of which 10 sheets of material, as for example tinned metal used in manufacture of containers, or cans, for storage of condensed milk, are automatically separated, one by one, from an assembled plurality, or pile, of such 15 sheets and thereafter moved to locations where operated on by other instrumentalities in the course of such manufacture, as, for example, to the machine employed to shape said sheets, or blanks, into the cylindrical body portions of said cans; and the 20 objects of my present improvements comprise provision of means whereby more rapidly, accurately, uninjiriously and economically the said separation and forwarding 25 of the individual sheets to their destination may be accomplished and with less manual exertion, and interference, by the operators than heretofore.

I attain these objects by the mechanisms 30 illustrated in the accompanying drawings, in which—

Figure 1 is a side elevation of my sheet-feeding machine, and of parts, diagrammatically illustrated, of a body-forming 35 machine therewith connected, certain parts being broken away to show interior;

Fig. 2 is an end view of my machine seen from the right hand of Fig. 1, the feeding 40 chain of said body-forming machine being also diagrammatically illustrated;

Fig. 3 shows a section of my machine taken on the line *a—a* of Fig. 2;

Fig. 4 is a plan view of the top of my 45 feeding devices and of a portion of the thereto adjacent end of said body-forming machine;

Fig. 5 shows a section of my feeding devices taken on the line *b—b* of Fig. 2;

Fig. 6 shows, on enlarged scale, a section 50 of part of the sheet-chute taken on the line *c—c* of Fig. 5, to show more fully the frictional stops controlling the settling of the sheets;

Fig. 7 shows a section of a portion of the 55 sheet-chute taken on the line *d—d* of Fig. 3,

to more fully illustrate the yielding means for supporting the sheets.

My novel machine, comprehensively indicated by A, is adapted to automatically separate, and withdraw, the sheets, one by 60 one, from the more or less bulky collection, or pile, in which they are customarily stored and moved, such separation and withdrawal of tinned-metal sheets, for example, being especially onerous for manual operation 65 owing to cohesion of the comparatively rigid sheets and their irritating edges. While accomplishing the foregoing, my machine simultaneously further advances, or feeds, each sheet, or blank, without handling, to a point whence producable therefrom any desired form, as, for example, to a well known can-body-forming machine which I have diagrammatically indicated as 70 B, comprising the usual feed rollers 1 and 2 (Figs. 3 and 4) which, after partly curling, deliver the blanks to a sub-disposed spindle 3 (Fig. 2) along which they are advanced by aid of a feed chain 4 carrying fingers 5 (Fig. 2) while being brought to 75 complete cylindrical shape by a tapering former 6 and their adjoining edges soldered, all of which mechanisms are too well understood to require further comment here, the object of referring thereto being merely 80 to give a concrete example of one well-known blank-manipulating instrumentality, the use of which my present invention is adapted to subserve automatically.

The sheets, or blanks, 7, to be operated 85 on, are received in the usual aggregations, stacks, or piles, which may be manually charged in bulk by the operator into my novel magazine, or sheet-chute, 8, where they afterward assume, relatively thereto, 90 the positions shown in Figs. 1, 3 and 5. This chute, carried by a bracket 9 secured to the body-forming machine B, comprises 95 four sides or walls, in this instance rectangularly disposed relatively to each other, is open at top *8^a* for charging, and at bottom *8^b* for discharging, and contains, disposed at an angle inclined from the perpendicular, a pathway dimensioned to contain, and admit passage therethrough of the 100 sheets while disposed in parallel planes angular to the longitudinal axis of said pathway.

The inclinations of the sheets while in 105 transit thereby secured is of great import-

tance in that it contributes to the gradual drop of each into its final position before removal as hereinafter described. Said inclination imposes the individual, and the aggregate, weight of the sheets, to a large extent, upon the inclined surface of the undermost side 10 (Fig. 5) of the chute, which side is provided with deflector stops 11, movably secured thereto by pivots 11^a, and projected 10 slightly into the pathway to required extent by adjusting screws 12.

Referring to the drawings, Figs. 5 and 6, it will be noted that, as therein shown, the deflector-stops 13 have projecting, downwardly and inwardly into the pathway, a graduated, or thereto inclined, rigid surface, shaped and disposed to bear against the uppermost edges of a plurality of sheets simultaneously, and upon each in turn as it 20 advances, with gradually increasing resistance until the apex of the incline or maximum resistance has been passed. This is of great importance as it tends to prevent the top of more than one sheet from passing the apex at a time, and meanwhile retards the tops of the following sheets as required.

It will also be noted that, as shown, the deflector-stops 11 have, at a level lower than that of said deflector-stops 13, projecting upwardly and inwardly into the pathway, an inclined surface shaped and disposed to bear against the lowermost edges of a plurality of the sheets simultaneously and thus gradually retard their descent in the chute. The 30 surfaces referred to of the stops 13, as compared with those of the stops 11, are inclined reversely relatively to each other.

Thus differences in the height of the sheets are to a large extent accommodated. Moreover, the resistance offered to the descent of the top of each sheet thus being gradually increased until it, in its turn, passes the point of maximum resistance, and the lowermost edge of the sheet being, meanwhile and 40 afterward, gradually increasingly retarded, serves to insure substantial loosening of each sheet from its neighbors and to prevent the tops of several mutually cohering sheets from simultaneously slipping by the apex of 50 the deflector-stops 13.

It is also of great importance that the relative degree of projection of the respective groups of deflector-stops into the pathway be adjustable, not only to meet requirements of different sized sheets, but more particularly to impart at the proper place and time the respective maximums of pressure against the respective topmost and lowermost edges of the sheets. This adjustment 60 is, by means of my construction and by aid of the set-screws 15, readily attained and maintained by those skilled in the art.

Similar deflector stops 13, similarly supported on pivots 13^a, are carried by the opposite wall 14 of the chute (Fig. 5) and are

similarly adjustable by means of set screws 15. It will be noted, as is of importance, that the deflector-stops 11 are located at a lower level than are the deflector stops 13, which disposition insures that the sheets are 70 temporarily checked in their descent while still in planes substantially angular to the central longitudinal axis of the pathway. The deflector-stops not only retard the gravity movement of the sheets, but also, because of the latter's aforesaid inclined position and the former's location relatively to each other operate to intermittently deflect from the bulk, or mass, one, or a few sheets, as indicated by dotted lines 7^a (Fig. 5), into 80 less inclined planes as at 7^b (Fig. 5) in which the superimposed weight is still less felt, and where a group of the then undermost sheets receives additional final retard and support from yielding means, to wit 85 stops 17, carried by the chute and having inwardly projecting resilient fingers 17^a (Fig. 7). The aggregate weight of the entire mass, or bulk, of sheets is thus not only diverted from the undermost members 90 thereof, but also the individual sheets are, during their descent, to an extent, parted, thus diminishing undue mutual adhesion, and, by suitably adjusting the deflector stops, as experience will in each instance 95 indicate, the rate of downward progression is retarded sufficiently to prevent clogging of my therewith coacting separating and placing device now to be described.

This operates to automatically and completely separate the sheets by removing, or picking them off, one by one, from the bottom of the advancing pile retarded, partially separated and supported, as above described, and to deposit them where required for further advance or feed. My said separator and placer comprises an oscillating arm 18 carrying, adjacent one end thereof, a pneumatic cup or sucker 19 (Fig. 3) disposed to pass through an opening 9^a (Figs. 3 and 4) in the tabular top of the bracket 9 and to operatively contact with the under surface of the lowermost sheet when the arm is oscillated to its upmost position, as indicated by dotted lines in Fig. 3. The required oscillation is imparted to the arm 18 by aid of an eccentric 23 and surrounding strap 24 connected with the arm by a link 25. A pivot 26, carried by bracket 27 supported by the bracket 9, oscillatably supports the 110 arm 18.

A rotatory shaft 28, operated by gears 29 and 30, (Fig. 2), the latter carried by a counter shaft 31 from any convenient source of power, carries said eccentric 23. To produce the required exhaust in the sucker 19, I provide an air pump, or exhauster, comprising a cylinder 32 and a therein reciprocating piston 33 (Fig. 1) connected by a link 34 with a wrist pin 34^a carried by a disk 35 120

carried by the shaft 28. A flexible tubing 36 (Fig. 1) connects the interior of the pump with a nipple 37 (Fig. 1) connecting with a duct 38 (Fig. 3) in the arm 18, which 5 duct connects with the interior of the pneumatic cup or sucker 19. The cylinder 32 is provided with an opening 39 through which air enters to break the exhaust when the piston 33 has been sufficiently lifted as 10 indicated in Fig. 1, and also with relief-openings 40 normally closed by a valve 41 movably supported on the threaded pin 41^a carried by the cylinder 32 and tensioned by the helical spring 42 encircling said pin and bearing against said valve and the adjustable nut 42^a. The rise of the piston is timed to exhaust the air in the cup 19 sufficiently to insure adherence thereto of a sheet when the cup is raised to contact therewith, as indicated 15 by dotted lines in Fig. 3. As the cup thereafter descends carrying therewith said sheet the latter encounters the tabular top of the bracket 9 which arrests and thereafter supports it in correct horizontal presentation, the further rise of the piston being 20 timed to, at this stage, pass the opening 39 and thus break the exhaust and release the sheet, while the unloaded cup continues its downward oscillation through the opening 25 9^a in said bracket.

A sheet having been, as aforesaid, automatically separated from the pile and placed upon the bracket, or rest, 9 is thereby movably supported without contact of a considerable portion, and more particularly of a part of the edge, of the sheet by said rest, being thus fitted for action thereon by my advancing device or kicker 44 (Figs. 2 and 4) which comprises a slide 45 reciprocatable 30 without contacting the sheet-supporting surface of said bracket or support, 9, and provided with fingers 46 extending transversely of and above and below the plane of the sheet when, as aforesaid, supported at rest 35 on the tabular top of the bracket 9. The slide is movably supported on guide rods 47 on each side of the opening 9^a (Figs. 2 and 4) and is actuated by aid of a therewith pivotally connected vibratory arm 49 (Fig. 40 3) having its lower end pivotally connected with a bracket 50 secured to the frame of the body-forming device B. While any part of the cup 19, or its therewith connected arm 18, is in, or passing through, the opening 9^a, this arm 49 is thrown, and held, backward, by a cam 51 carried by the shaft 28 thus clearing said opening of the fingers 46, but the cam is so shaped, as shown, and its rotation so timed, that when the sheet has been 45 deposited, and left, in place on the horizontal tabular top of the bracket 9, a powerful retractile spring 52, connecting the bracket 9 with said bar 49, smartly impels the latter forward thereby causing said fingers 46 to strike a sharp blow horizontally against one

edge of the sheet whereby it is projected, in a substantially horizontal plane, into the grasp of the feed rollers 1 and 2, of the body-forming machine.

By reference to the drawings, particularly Fig. 5, it will be seen that the construction is such that operative portions, or fingers, 46, of the kicker 44 are advanceable, without contacting the sheet-supporting surfaces of the bracket 9, in a path in alinement with, and extending beyond, the normal location of said unsupported part of the edge of the sheet; and that the shape of the cam is such that, by aid of the spring 52, the kicker is impelled in said path to strike a sweeping, percussive blow against said edge, and to "follow through" beyond its said normal location, thereby causing the sheet to take flight in a predetermined direction.

The spring-tensioned quality of the blow against the edge of the sheet is of great importance, not only because it is not positive, and unyielding, but, also, particularly because of its springy "following-through" character, which imparts a very perfect flight to the sheet with less danger of deforming the edge than if the kicker were actuated by more positively operating means.

The position and resilience of the fingers 17^a of the stops 17 is such as to enable them to retain between them any number of sheets while the lowermost adheres to and is pulled out by the sucker 19, the suction being correspondingly regulated.

As clearly shown by Fig. 7 of the drawings, the fingers 17^a principally actually support the lowermost sheet and thus also the stack of thereon imposed mutually parallel sheets which are at the same inclination, and which, were the fingers removed, would fall in mass upon the tabular top of the bracket 9. But owing to the inclination of said lowermost sheet, and the circumstance that its lowermost edge is then encountering the maximum resistance of the deflector-stops 11, the load otherwise imposed by the stack upon the fingers is so far reduced as to enable the latter to support it, and also so yieldingly as to readily release said lowermost sheet only and without its being materially, if at all, bent in its passage through the fingers. In aid of this desirable result, I have, as clearly shown in Fig. 7, shaped the fingers so as to project, into the path of the sheet, oppositely disposed, coacting, curved surfaces which are convex toward the side edges of the sheet, and located as shown at the terminals of the lead lines from the reference numerals 17^a in said Fig. 7. These curvatures of the resilient fingers provide a graduated yielding clutch upon a plurality of the sheets and a maximum clutch, or bearing, impartable to one only, i. e., the lowermost, of the sheets. It follows that while the fingers readily yield sufficiently to per-

mit the pneumatic cup, with comparatively slight force, to pull the lowermost sheet from between them, their resilience returns them toward normal position so promptly, 5 and their curvature is such, that immediately after the then lowermost sheet has passed the zone of maximum clutch, the next sheet and its followers are gradually checked from following, and in turn supported sufficiently 10 until the return of the cup. Thus, also, should the pneumatic cup, by reason of inaccurate adjustment of its oscillating mechanism, bear up so heavily against the lowermost sheet as to abnormally lift it, and the 15 superimposed stack, the latter is returned by gravity to its normal position and without any such jar against the retaining devices as might cause the stack, or parts thereof, to break through them and thus clog the 20 machine.

It will be noted that the kicker is incompetent to project the sheets to desired location with industrial economy, precision and success, unless the sheets are by coöperation 25 of the chute and its adjuncts, and of the separating and placing devices described, separated, adjusted and horizontally supported with sufficient rapidity and exactness to enable the kicker to properly do its work. 30 In short, none of my said devices would, I believe, prove of equal, or important, value, on industrial scales of manufacture, unless combined and coöperating with each other as I have shown and described. At the 35 same time I do not wish to be understood as confining myself to the particular forms and arrangement of devices shown in the drawings, since I regard variations therefrom operating in the same way to produce the same 40 results as within the purview of my invention, which having now described, as aforesaid, I claim as follows, viz.:

1. In a sheet-feeding machine, a chute comprising opposite parallel inclined sides 45 having between them an inclined sheet-pathway dimensioned to admit passage therethrough by gravity of a stack of mutually-contacting sheets, the lowermost edges of which bear against the lowermost of said 50 sides; carried by the uppermost of said sides at a therein medial location a deflector-stop having, projecting downwardly and inwardly into said pathway, an inclined surface shaped and disposed to bear against the 55 uppermost edges of a plurality of said sheets simultaneously and gradually retard their descent in the chute; and, carried by the lowermost of said sides at a level lower than that of said deflector-stop, another deflector- 60 stop having, projecting upwardly and inwardly into said pathway, a convex inclined surface shaped and disposed to bear against the lowermost edges of a plurality of said sheets simultaneously and gradually retard 65 their descent in the chute.

2. In a sheet-feeding machine, a chute comprising opposite parallel inclined sides having between them an inclined sheet-pathway dimensioned to admit passage therethrough by gravity of a stack of mutually-contacting sheets, the lowermost edges of which bear against the lowermost of said sides; carried by the uppermost of said sides a deflector-stop having, projecting downwardly and inwardly into said pathway, an inclined surface shaped and disposed to bear against the uppermost edges of a plurality of said sheets simultaneously and gradually retard their descent in the chute; and means to adjust and maintain the degree of projection of said surface of the deflector-stop into the pathway. 70

3. In a sheet-feeding machine, a chute comprising opposite parallel inclined sides having between them an inclined sheet-pathway dimensioned to admit passage therethrough by gravity of a stack of mutually-contacting sheets, the lowermost edges of which bear against the lowermost of said sides; carried by the uppermost of said sides 80 a deflector-stop having, projecting downwardly and inwardly into said pathway, an inclined surface shaped and disposed to bear against the uppermost edges of a plurality of said sheets simultaneously and gradually retard their descent in the chute; carried by the lowermost of said sides at a level lower than that of said deflector-stop, another deflector-stop having, projecting upwardly and inwardly into said pathway, an inclined surface shaped and disposed to bear against the lowermost edges of a plurality of said sheets simultaneously and gradually retard their descent in the chute; and means to independently adjust and maintain the degree of projection of said surfaces of the deflector-stops relatively to each other in the pathway. 85

4. In a sheet-feeding machine, a chute comprising opposite parallel inclined sides having between them an inclined sheet-pathway dimensioned to admit passage therethrough by gravity of a stack of mutually-contacting sheets, the lowermost edges of which bear against the lowermost of said sides; carried by the lowermost of said sides 90 adjacent the outlet of said chute a deflector-stop having, projecting upwardly and inwardly into said pathway an inclined surface shaped and disposed to bear against the lowermost edges of a plurality of said sheets simultaneously and gradually retard their descent in the chute; and, adjacent the outlet of said chute, a pair of fingers shaped and disposed to project oppositely to each other into said pathway and to bear against the opposite side-edges of said sheets at a level above that of the maximum projection of said surface of said deflector-stop into said pathway. 95

5. In a sheet-feeding machine, a chute 100

comprising opposite parallel inclined sides having between them an inclined sheet-pathway dimensioned to admit passage therethrough by gravity of a stack of mutually-contacting sheets, the lowermost edges of which bear against the lowermost of said sides; carried by the lowermost of said sides adjacent the outlet of said chute a deflector-stop having, projecting upwardly and inwardly into said pathway an inclined surface shaped and disposed to bear against the lowermost edges of a plurality of said sheets simultaneously and gradually retard their descent in the chute; and, adjacent the outlet of said chute, a pair of yielding, resilient, fingers shaped and disposed to project oppositely to each other into said pathway and to bear against opposite side-edges of said sheets at a level above that of the maximum projection of said surface of said deflector-stop into said pathway.

6. In a sheet-feeding machine, a chute comprising opposite parallel inclined sides having between them an inclined sheet-pathway dimensioned to admit passage therethrough by gravity of a stack of mutually-contacting sheets, the lowermost edges of which bear against the lowermost of said sides; carried by the lowermost of said sides adjacent the outlet of said chute a deflector-stop having, projecting upwardly and inwardly into said pathway an inclined surface shaped and disposed to bear against the lowermost edges of a plurality of said sheets simultaneously and gradually retard their descent in the chute; and means to yieldingly support and retard advance of the side-edges of the sheets while their lowermost edges are bearing against said surface of said deflector-stop in said pathway.

7. In a sheet-feeding machine, a chute comprising opposite parallel inclined sides having between them an inclined sheet-pathway dimensioned to admit passage therethrough by gravity of a stack of mutually-contacting sheets, the lowermost edges of which bear against the lowermost of said sides; carried by the lowermost of said sides adjacent the outlet of said chute a deflector-stop having, projecting upwardly and inwardly into said pathway an inclined surface shaped and disposed to bear against the lowermost edges of a plurality of said sheets simultaneously and gradually retard their descent in the chute; and, adjacent the outlet of said chute, a pair of fingers shaped and disposed to project oppositely to each other into said pathway convexly curved surfaces to bear against opposite side-edges of said sheets at a level above that of the maximum projection of said surface of said deflector-stop into said pathway.

8. In a sheet-feeding machine, a chute comprising opposite parallel inclined sides having between them an inclined sheet-path-

way dimensioned to admit passage therethrough by gravity of a stack of mutually-contacting sheets, the lowermost edges of which bear against the lowermost of said sides; carried by the uppermost of said sides a deflector-stop having, projecting downwardly and inwardly into said pathway, an inclined surface shaped and disposed to bear against the uppermost edges of a plurality of said sheets simultaneously and gradually retard their descent in the chute; carried by the lowermost of said sides at a level lower than that of said deflector-stop, another deflector-stop, having projecting upwardly and inwardly into said pathway, an inclined surface shaped and disposed to bear against the lowermost edges of a plurality of said sheets simultaneously and gradually retard their descent in the chute; and means to yieldingly support and retard advance of the side-edges of the sheets while their lowermost edges are bearing against said surface of said last mentioned deflector-stop in said pathway.

9. In a sheet-feeding machine, a chute comprising opposite parallel inclined sides having between them an inclined sheet-pathway dimensioned to admit passage therethrough by gravity of a stack of mutually-contacting sheets, the lowermost edges of which bear against the lowermost of said sides; carried by the uppermost of said sides a deflector-stop having, projecting downwardly and inwardly into said pathway, an inclined surface shaped and disposed to bear against the uppermost edges of a plurality of said sheets simultaneously and gradually retard their descent in the chute; carried by the lowermost of said sides at a level lower than that of said deflector-stop, another deflector-stop having, projecting upwardly and inwardly into said pathway, an inclined surface shaped and disposed to bear against the lowermost edges of a plurality of said sheets simultaneously and gradually retard their descent in the chute; and, adjacent the outlet of said chute, a pair of yielding, resilient fingers shaped and disposed to project oppositely to each other into said pathway and to bear against opposite side-edges of said sheets at a level above that of the maximum projection of said surface of said last mentioned deflector-stop.

10. In a sheet feeding machine, a chute comprising opposite parallel inclined sides having between them an inclined sheet-pathway dimensioned to admit passage therethrough by gravity of a stack of mutually-contacting sheets, the lowermost edges of which bear against the lowermost of said sides; carried by the uppermost of said sides a deflector-stop having, projecting downwardly and inwardly into said pathway, an inclined surface shaped and disposed to

bear against the uppermost edges of a plurality of said sheets simultaneously and gradually retard their descent in the chute; carried by the lowermost of said sides at a 5 level lower than that of said deflector-stop, another deflector-stop having, projecting upwardly and inwardly into said pathway, an inclined surface shaped and disposed to bear against the lowermost edges of a plurality of 10 said sheets simultaneously and gradually retard their descent in the chute; and, adjacent the outlet of said chute, a pair of yield-

ing, resilient, fingers shaped and disposed to project oppositely to each other into said pathway and having convexly curved surfaces to bear against opposite side-edges of said sheets at a level above that of the maximum projection of said inclined surface of said last mentioned deflector-stop.
